HIGH FREQUENCY SYSTEM

Alfred Wiessner and Wolfgang Hagen, Berlin, Germany, assignors to C. Lorenz Aktiengesellschaft, Berlin-Tempelhof, Lorenzweg, Germany, a company

Application May 13, 1938, Serial No. 207,758
In Germany May 20, 1937

2 Claims. (Cl. 179—2.5)

The present invention relates to high frequency systems, and more particularly to an arrangement for receiving messages transmitted by means of high frequency carrier waves over cables.

5 The intelligence transmission over line networks by means of high frequency carrier currents, the so-called wire-radio, is well known. These carrier frequencies are impressed upon a telephone network, in an exchange office, for instance, and are again derived from the network in the receiving positions by the aid of electric separating filter devices. Generally, a plurality of different frequencies is simultaneously impressed upon a line network so that the receiving 10 positions must be provided with filtering means for again separating the various carrier frequencies. It has been found that the circuits employed in broadcasting receivers of standard type are not sufficiently selective for effecting 15 the necessary separation.

20 It has therefore been suggested to furnish receiving devices for wire-radio systems with band filters which are adapted to selectively be rendered effective and ineffective so as to pass merely one single of a plurality of frequency bands, but this expedient becomes disadvantageous in cases that the wavelengths of a transmitter are subjected to variations, since matching to a changed wavelength involves considerable difficulties so 25 that reliable passing ranges will be obtained in such units only by the provision of complicated expenditures. Moreover, it has been proposed to provide the receiving positions with an oscillatory circuit the inductance of which having tapping 30 points so as to obtain adjustability to different frequencies. However, this arrangement introduces the disadvantage that frequency adjustments cannot be made independently of one another and, moreover, that a distinctive separation 35 free of cross talks cannot be obtained between the frequencies transmitted over cables.

These disadvantages are avoided according to the present invention which proposes the use of adjustable oscillatory circuits in the receiving 40 equipments, said oscillatory circuits being so arranged that one thereof acts as selective circuit while the other are effective as rejector circuits.

The invention will be more readily understood from the following description taken in conjunction with the accompanying drawing in 45 which

50 Fig. 1 is a diagrammatic representation of one embodiment according to the invention, Fig. 2 diagrammatically illustrates a modification over 55 the arrangement shown in Fig. 1, Fig. 3 is an

explanatory representation with respect to certain frequency conditions, Fig. 4 diagrammatically shows a coupling circuit according to the invention, while Fig. 5 diagrammatically shows still a further modification.

The Fig. 1 illustrates a corresponding arrangement which comprises three resonance circuits 1, 2 and 3 of the parallel type and connected in series. The high frequency supplied over the line is conveyed to these circuits over the transformer 10. Each of the three resonance circuits 1, 2 and 3 is tuned to one of the frequencies transmitted over the line and is connected to the succeeding portion of the receiving equipment in any suitable manner. The received wave is derived across the 15 resonance circuit tuned thereto. Since the other two resonance circuits are tuned to the incoming frequencies which are to be separated, these circuits will act as rejector circuits so that a high quality selective effect will be obtained. 20

The Fig. 2 illustrates a particularly suitable embodiment according to the invention. Three resonance circuits 5, 6 and 7 of the series type are used and connected in parallel with each other. The high frequency incoming over the 25 line network is applied to these circuits over the transformer 4. The high frequency is derived from the above mentioned resonance means between the grounded point E and the not grounded end of the inductance of the oscillatory circuits. 30 A switch 9 may, for instance, serve for connecting these circuits to the input side of the broadcasting receiver 10. Also in this case the resonance circuit connected to the receiver acts as selective circuit while the two other circuits 35 in parallel thereto act as by-pass circuits. The characteristic impedance of the line is matched to the resonance circuits by means of the repeater 4. 40

The arrangement shown in the drawing may be used as an additional member to a standard broadcasting receiver, for instance, by providing the arrangement in a suitable box. It is also possible to utilize this arrangement as an input circuit for a specific wire-radio receiver in which 45 the tuning circuits are directly connected to the first amplifying tube.

In cases that the arrangement would not present the required selectivity it is also within the scope of the invention to arrange the filter 50 circuits in a plurality of stages and to connect these in a tandem fashion. The individual stages may be conjointly set by any suitable means.

If the frequency of one or more of the transmitted waves should be subjected to variations, 55

the resonance circuits may be correspondingly tuned to the new frequency by means of an adjustment of the condenser forming part of the circuit.

- 5 The Fig. 3 illustrates the resonance curves of the filtering circuits shown in Figs. 1 and 2. Investigations have proven that, e. g., on using three frequencies of 150, 180 and 220 kilocycles differences prevail with respect to the sharpness 10 of the resonance curves since the width increases at the higher frequencies. In order to obtain equal curves for these three frequencies, a requirement which is necessary for matching the low-frequency portion, it is possible to insert additional ohmic resistances in one or more of the resonance circuits as shown by resistances 21 and 22 in Fig. 5 which is later described in detail, or to correspondingly dimension the inductance to capacity ratio.
- 20 The higher frequency range of the low-frequency band transmitted by the agency of the carrier frequencies are generally attenuated due to the shape of the resonance curve as shown in Fig. 3. In order to compensate the attenuation 25 of the higher frequencies and in accordance with a further feature of the invention a coupling device is provided in one of the low-frequency stages as illustrated in Fig. 4. This figure shows a typical low frequency amplifier tube 12. By 30 low frequency is meant a frequency which is of a different and lower order from the frequency of the wave received over the line. Thus, for example, the tube 12 may represent a conventional audio frequency amplifier tube which follows the 35 usual detector stage in a high frequency receiver. This coupling means 13 is connected between the tubes 11 and 12, the transit time of this means being adapted to compensate the distortion of the message band set up in the high frequency filtering circuits. The inductance 14 which is 40 jointly active with the ohmic resistances 15, 15', and 15'' presents an alternating current resistance which increases with frequency so that the control voltage of the tube 12 also increases with 45 frequency.

Still another embodiment according to the invention is shown in Fig. 5 according to which a selective action corresponding to that shown in Fig. 2 is accomplished in the three parallel tuning circuits 17 in front of the first tube 16, while a further selective action is effected in the three

serially arranged resonance circuits 19 in front of the second tube 18 which may be a tube of a detector stage. The output of tube 18 is coupled by means of condenser 23 and resistance 24 to a low frequency portion of the type shown in 5 Fig. 4. The inductance coils of the resonance members of the three serially connected selective circuits 19 are simultaneously employed as primary windings of repeaters 20 which serve as coupling to the succeeding amplifying stage. 10 Cores of high frequency iron may be used in these repeaters in case of need. Also in the arrangement shown in Fig. 5, the individual circuits may be conjointly adjusted, e. g., by means of a knob common thereto.

The resonance circuits of the various stages may furthermore be somewhat de-tuned relative to one another so as to obtain a band filtering effect for each of the three frequency ranges.

What is claimed is:

1. In a high frequency system, a receiving device for messages transmitted over cables by means of high frequency carrier waves, said device comprising an incoming line, a number of oscillatory circuits arranged in stages and having inductances and capacities one of said stages including oscillatory circuits connected in series and a further one of said stages including oscillatory circuits connected in parallel to one another, a low-frequency portion having coupling means 20 and being coupled to said stages, means for selectively rendering one of said oscillatory circuits of each stage effective as a selective circuit and simultaneously rendering the remainder of said series oscillatory circuits effective as rejector circuits and the remainder of said parallel oscillatory circuits effective as by-pass circuits, and resistances included in the individual oscillatory circuits and adapted to provide equal resonance characteristics for all oscillatory circuits, said coupling means of said low-frequency portion being dimensioned so as to compensate distortions set up in the rejector and by-pass circuits.

2. In a high frequency system, a receiving device as defined in claim 1, in which the resonance 45 circuits in the different stages are somewhat de-tuned relative to each other so as to produce a band filter effect.
